UNITED STATES PATENT OFFICE.

PHILIP MUELLER, OF DECATUR, AND ANTON C. SCHUERMANN, DECEASED, LATE OF DECATUR, ILLINOIS, BY HELENA SCHUERMANN, EXECUTRIX, OF DECATUR, ILLINOIS, ASSIGNORS TO ADOLPH MUELLER, TRUSTEE, OF DECATUR, ILLINOIS.

SELF-CLEANING FLUSHING VALVE.

Application filed October 17, 1925. Serial No. 63,185.

- This invention relates to flushing valves of the direct connected, retarded action type. Valves of this type are designed to receive from a suitable supply and discharge a definite volume of water, and then close automatically, the closing movement being retarded to give complete discharge. One object of this invention is to provide a device for effectively regulating the duration of flow while the valve is discharging; and to provide with positive and effective means for keeping the drain port of the regulating device free from objections; while a further object is to provide a preliminary valve, acting in conjunction with the flow regulating device, which will function to prevent sudden closing of the main valve.
- In the drawings herewith we have illustrated one embodiment of our invention, and in said drawings:
- Fig. 1 is a vertical section of our improved valve.
- Fig. 2 is a sectional plan taken on the line 2—2 of Fig. 1.
- Fig. 3 is a detail sectional view of the flow regulating device.
- Fig. 4 is a section taken on the line 4—4 of Fig. 3.
- Fig. 5 is a section taken on the line 5—5 of Fig. 1, looking in the direction of the arrow.
- Referring to the drawings, in which like parts are designated by like reference numbers, 10 indicates the valve casing, which has a screw threaded inlet opening 11 to which the supply pipe 12 leading from the main or other source of supply of water under pressure is connected, and a screw threaded outlet opening 13 to which is connected the pipe 14 discharging to a water closet bowl (not shown) or other suitable point of discharge. Extending from the inlet 11 is a chamber 15, which is closed at its upper end except for a reduced opening 16 having a valve seat 17 at its under side. Formed on the inner wall of the inlet chamber 15, and equidistantly disposed thereabout, are a plurality of radially projecting ribs 18, which extend downwardly from the valve seat 16 to the lower end of the inlet chamber and serve as guides for a reciprocating valve 19, at the same time providing clearance spaces 20 between the valve 19 and the wall of the inlet chamber through which water may pass.
- Extending upwardly from a point below the valve seat 16, the casing 10 is enlarged to form a piston chamber or cylinder 21, which partially surrounds the valve seat and the upper end of the inlet chamber 15, and is provided with a flanged upper end, screw threaded, as at 22, to receive a union coupling nut 23, by means of which nut a bonnet 24 is detachably secured to the casing 11.
- Formed in the wall of the casing 10 is a water passage way 25 communicating at its lower end with the inlet chamber 15, below the valve seat, and extending around the valve seat to the upper end of the casing 10. At its upper end said passage 25 communicates with another water passage-way 26 formed in the body of the bonnet 24. The passage-way 26 communicates with an upwardly extending enlarged valve chamber 27 axially aligned with the cylinder 21, the valve seat 16 and the inlet chamber 15. The valve chamber 27 has a valve seat 28 against which a spring closed auxiliary valve 29, having the actuating handle 30, and adapted, when closed, to exclude water from the chamber 27 is adapted to seat. Leading from the chamber 27 into the upper end of the cylinder 21 at one side thereof is the passage 31. A depending lug 32 is formed on the face of the bonnet 24 which seats in a socket 33, thereby serving to center the parts in assembling and bring the passage way 26 of the bonnet 24 into registry with the passage way 25 of the casing 10.
- Preferably, a flexible gasket 34, having an opening fitting over the projection 31, and a port 36, so located as to register with the passage-ways 25 and 26, and thus provide a passage from the inlet chamber 15 to the valve seat 28, is interposed as shown to seal the joint between the upper end of the casing 10 and the bonnet 24.
- The main valve 19 comprises a cup-shaped incasing member 37, a flexible seat washer 38, having in the present instance a conical face, and a metal preliminary valve disk provided with the flanged part 39 of the same

diameter as the valve seat open 16, and an extension 40, of less diameter than the seat opening, which extension has in its outer face a recess 41.

5 The main valve stem 42 has formed at its lower end a flange 43 and a reduced extension 44, which extends downwardly from the flange 43, and is screw threaded at its end to receive a nut or other suitable fastening device. At the upper end of the stem 42 is another flange 45 and a screw threaded projection 46 extending upwardly from the flange 45. In the end of projection 46 is a passage 47, screw threaded at its upper end, 10 which continues down through the stem 42 to terminate in a lateral outlet opening 49, below the flange 45, through which may be drained from the upper part into the lower part of the cylinder 21.

15 20 Each of the main valve members 37, 38 and 39 is centrally apertured so that the reduced extension 44 of the valve stem 42 may be inserted therethrough. To assemble these members, the metal preliminary valve member 39, the seat washer 38, and the incasing member 37 are placed on the reduced extension 44 in the order named and secured in position by the nut 50. The flange 43 of the stem 42 seats in the recess 43 in the face of 25 the extension 40 of the metal preliminary valve member, and the seat washer 38 is securely clamped between the preliminary valve 39 and the inner face of the incasing member 37.

30 35 The preliminary valve 39, serves a double purpose, in that, first, it effects a gradual throttling of the flow, thus preventing "water hammering", which would follow the sudden stoppage of the water flowing through the valve under pressure at a high velocity; and, secondly, the diminished supply of water passing about the preliminary valve, after the bowl has been flushed, flows into the bowl and provides the refill for the 40 45 trap or water seal chamber. The arrangement just described provides a very durable valve; and one which may be readily repaired, as the seat washer 38, which is the part subjected to greatest wear, may easily be replaced when worn.

50 55 Mounted on the screw threaded extension 46 of the valve stem 42 is a flexible cup piston comprising a metal disk-like member 51, having formed thereon two or more oppositely disposed depending stop fingers 52, a flexible cup 53 and another metal disk 54, all centrally apertured to fit over the screw threaded projection 46, and clamped together by a nut 55 screw threaded on the 60 end of the projection 46. As shown in Fig. 1 of the drawing, the member 51 rests against the flange 45 of the stem 42 and the flexible cup 53, which is of such diameter as to closely fit within the cylinder 21, is securely 65 clamped between the metal disks 51 and 54.

The stop fingers 52 are so spaced, diametrically, as to about the end of the inlet chamber 15 to stop the downward movement of the piston and thus limit the extent of opening of the main valve 19.

70 It will be observed that the construction of the piston is such as to facilitate the replacement of the flexible cup 53 when it becomes worn. Upon removal of the bonnet 24, the piston, valve stem 42 and main valve 75 19 may be removed from the casing, without difficulty.

80 In order to regulate the duration of flow through the main valve seat opening 16, a specially constructed regulating device carried by the valve stem 42 is provided, as shown in Figs. 1, 2, 3 and 4. In the construction of this regulating device, a casing 57 having inlet ports 58 and a reduced extension 59 is provided, which casing is screw 85 threaded into the upper end 46 of the stem 42 and closed by an end wall 60, except for a small outwardly flaring port 61. An exterior shoulder 63 is formed at the point where the wall of the reduced extension 59 merges into that of the enlarged body of 90 the casing 57. The outer end of this casing is screw threaded to receive a closure cap 64. The closure cap 64 has a central aperture through which projects the head of a plunger 66, which has an integral flange 67, and extending downwardly from this flange is a triangular shank 68, having formed on or secured to its extreme lower end a port 95 cleaning pin 69, in line with, and adapted to be automatically forced through the outlet port each time the main valve 19 and its piston moves upward to closed position, to keep this port clear of sediment or foreign matter that may collect therein and clog the 100 port. By means of a helical compression spring 70, one end of which rests against the shoulder 63 and the other end against the lower face of the flange 67, the plunger 66 is retracted to withdraw the cleaning pin 69 from the port 61 each time the main valve moves downwardly and is opened. When the valve stem 42 moves upwardly to close the main valve the pin 69 will be forced 105 through the port 61 by the plunger 66 striking against the inner face of the bonnet 24, and any sediment or other foreign matter lodged in the port 61 will be forced out into the enlarged flared opening 63 through which it will fall into the outlet passage 110 115 49, to be washed away.

120 To flush the closet bowl it is necessary only to turn the handle 30, which may be of any desired type, but preferably of the quick compression type, and thus withdraw the auxiliary valve 29 from its seat 28. Water under pressure will then flow from the inlet chamber 15 through passage ways 25, 26, port 28, and passage 31, into the cylinder 21 above the flexible piston cup 53 and force 125 130

the piston downwardly, carrying with it the valve stem 42 through which the main valve 19, by reason of the fact that its area is considerably less than that of the piston 5 will be forced downwardly away from its seat until the stop fingers 52 come into contact with the end of the inlet chamber 15, and limit downward movement of the valve. With the main valve 19 now open, water begins to flow through port 16 and flushing pipe 14 into the bowl, or other point of delivery. At the same time the cleaning pin 69 having been withdrawn by the spring 70 from the outlet port 61 in the bottom of the 15 casing of the flow regulating device, and the auxiliary valve 29 having, through release of handle 30, returned to its seat, the water trapped in the cylinder 21 above the piston will begin to drain into the casing 20 57 through the inlet ports 58 and pass through the channels 68 formed between the wall of the reduced part 59 of the casing and the flat sides of the triangular shank 68, finally escaping through port 61, lateral 25 opening 49, and pipe 14, into the bowl. The pressure above the piston is thus gradually relieved to such an extent that the pressure in the inlet chamber 15, aided by the induced suction through the port 16, forces the 30 main valve 19 toward its seat, the water cushion above the piston retarding such closing movement, since the water forming the cushion is forced slowly out through the relatively small drainage port 61, as described. As the extension 40 of the valve 35 enters the opening 16 and restricts the flow, the greater volume of water discharged into the bowl, will, through siphonage, be drawn from the trap of the bowl into the pipe leading to the sewer, and the water remaining will then flow into the bowl and refill the trap. The flanged part 39 of the preliminary valve then seats in the port 16 and substantially shuts off the flow, so that the 40 main valve 19 can not be drawn suddenly to its seat, by suction, with a hammering action. Before the valve 19 reaches its seat the plunger 66 comes into contact with the bonnet 24 and forces the pin 69 into the 45 port 61, thus not only removing any clogging matter therefrom, but also choking the flow through this port to such an extent with a resultant slowing down of the upward movement of the piston, as to aid the preliminary valve 39, in retarding the flow through the main valve seat opening 16, so that the valve 19 will move more slowly to its seat.

It will be seen that there is direct cooperative relationship between the preliminary valve 39, and the flow regulating device, in that they function together in retarding the closing movement of the main valve 19.

We are aware of the fact that it is old in the art to employ a wiper rod to clean the drain port of the flow regulator. However,

in such structures, it has been customary to make the wiper rod of such length that it would not at any time be entirely withdrawn from the port. Such a cleaning device is ineffective, because the wiper rod, 70 remaining always in the drain port, is gradually enlarged by the accumulation thereof of sediment so that finally it completely fills and closes the port. Obviously, unless the end of the wiper rod is brought to bear 75 against an accumulation of sediment or other foreign matter, such matter will adhere to the wiper rod and the wall of the port and gradually fill in between them so as to practically prevent drainage. 80

In the construction of regulator herein shown, the cleaning pin 69 is entirely withdrawn from the drain port 61 each time the main valve is opened and is always effective to clear the port of accumulated matter. 85

Although we have described our improved valve in connection with the flushing of water closet bowls, it is to be understood that the principles of the invention may be embodied in faucets or other valves in which 90 it is necessary or desirable to have the valve deliver a definite quantity of water or other liquid and then close automatically.

It will be understood, further, that a diaphragm may be used instead of the flexible 95 cup piston shown with the same results as described in the foregoing specification, and, therefore, the term "piston" in the claims is to be regarded as synonymous with "diaphragm". 100

It is obvious that various changes in form, proportions, and minor details of construction, may be resorted to within the scope of the appended claims.

We claim:

1. In a valve mechanism, the combination of a casing having an inlet chamber and a piston chamber, a main valve seat between said chambers, a discharge outlet from said piston chamber, a piston in said piston chamber, a valve controlling said main valve seat carried by said piston, a by-pass from the inlet chamber to the piston chamber in rear of the piston, an auxiliary valve in said by-pass, a drainage passage through said piston having a reduced outlet port, and means carried by said piston automatically to further reduce said outlet port prior to the complete closing of the main valve. 110

2. In a valve mechanism, the combination of a casing having an inlet chamber and a piston chamber, a main valve seat between said chambers, a discharge outlet leading from said piston chamber, a piston in said piston chamber, a valve controlling said main valve seat carried by said piston, a by- 115

pass from the inlet chamber to the piston chamber in rear of the piston, an auxiliary valve in said by-pass, a drainage passage through said piston having a reduced outlet 120 port. 125

port, and means carried by said piston and caused by engagement with the casing automatically to enter said port.

3. In a valve mechanism, the combination 5 of a casing having an inlet chamber and a piston chamber, a main valve seat between said chambers, a discharge outlet leading from said piston chamber, a piston in said piston chamber, a valve controlling said 10 main valve seat carried by said piston, a by-pass from the inlet chamber to the piston chamber in rear of the piston, an auxiliary valve in said by-pass, a drainage passage through said piston having a reduced outlet 15 port, a cleaning pin mounted in said drainage passage in alignment with said outlet port and so disposed as to be forced through said port by contact with the end of the piston chamber when the main valve is moved 20 to its seat, and a compression spring for withdrawing said pin from said port when said main valve is moved away from its seat.

4. In a valve mechanism, the combination 25 of a casing having an inlet chamber and a piston chamber, a main valve seat between said chambers, a discharge outlet leading from said piston chamber, a piston in said piston chamber, a valve controlling said 30 main valve seat carried by said piston, a by-pass from the inlet chamber to the piston chamber in rear of the piston, an auxiliary valve in said by-pass, a drainage passage through said piston having a reduced outlet 35 port, a plunger mounted in said drainage having a reduced passage, a cleaning pin carried by said plunger and operable to clean said port, and a compression spring normally holding said plunger in retracted 40 position with said cleaning pin withdrawn from said outlet port.

5. In a valve mechanism the combination 45 of a casing having an inlet chamber and a piston chamber, a main valve seat between said chambers, a discharge outlet leading from said piston chamber, a piston in said piston chamber, a valve controlling said main valve seat carried by said piston, a by-pass from the inlet chamber to the piston 50 chamber in rear of the piston, an auxiliary valve in said by-pass, a drainage passage through said piston having a reduced outlet port, a cleaning device carried by said piston comprising a casing mounted in said 55 drainage passage and having a reduced outlet port, a plunger having an abutment mounted in said casing, a cleaning pin in alignment with said outlet port carried by said plunger, a compression spring engaging 60 said abutment to hold said plunger in retracted position, and means to engage the opposite face of said abutment and limit the outward movement of said plunger.

6. In a valve mechanism, a headed cylinder, a valve connected piston therein, means

for forming a water cushion to the rear of the piston upon opening the valve, a reduced outlet in said piston for the escape of said cushion upon the valve and piston return, and a retractive pin carried by said piston 70 and adapted to abut the cylinder head to be forced into said outlet for further reducing the latter prior to the complete return of the valve and piston.

7. In a valve mechanism, the combination 75 of a casing having an inlet chamber and a piston chamber, a main valve seat between said chambers, a piston in said piston chamber, a valve stem carried by said piston, a drainage passage in said valve stem leading from one side of said piston to the other, a casing mounted in said drainage passage having inlet ports and a reduced outlet port, a plunger having a projecting end mounted in said casing, a cleaning pin at the other 80 end of said plunger in alignment with but normally withdrawn from said reduced outlet port, an abutment on said plunger, a compression spring between said abutment and the end of said casing, and a main valve 85 mounted on the opposite end of said valve stem having a preliminary section adapted to enter the main valve seat ahead of the main valve and gradually restrict flow therethrough.

8. In a valve mechanism, the combination 90 of a casing having an inlet chamber and a piston chamber, a main valve seat between said chambers, a discharge outlet leading from said piston cylinder, a piston in said piston chamber, stop means on said piston to engage a wall of the inlet chamber, a valve stem carried by said piston, a valve carried by said stem and having a disc section adapted to enter and partially close the said main 95 valve seat ahead of the main valve, a flow regulating device mounted in the end of said valve stem adjacent said piston and having a casing provided with an inlet port and a reduced outlet port, a plunger in said casing 100 having a cleaning pin in alignment with said reduced outlet port, an abutment on said plunger, and a compression spring for normally holding said plunger in retracted position.

9. In a valve mechanism, the combination 105 of a casing having an inlet chamber and a piston chamber, a supply-passage leading to said inlet chamber, a discharge passage leading from said piston chamber, a by-pass 110 from said inlet chamber to said piston chamber, a valve in said inlet chamber having a preliminary section to restrict flow through the port from said inlet chamber to said piston chamber in advance of the complete seating of the valve, a valve stem extending into said piston chamber, a piston mounted on said valve stem, a drainage passage from one to the other side of said piston, a regulator to control flow through said passage,

and means to operate said regulator and restrict flow through said passage substantially simultaneously with the entrance of the preliminary valve section into the port in said inlet chamber.

In testimony whereof, we PHILIP MUELLER and HELENA SCHUERMANN, executrix of the

last will and testament of ANTON C. SCHUERMANN, deceased, have hereunto set our hands.

PHILIP MUELLER.

HELENA SCHUERMANN,

Executrix of Anton C. Schuermann, deceased.
